UNITED STATES PATENT OFFICE.

ANGUS A. MACLENNAN, OF BUENA VISTA, COLORADO.

STOVEPIPE-CLEANER.

1,000,737.

Specification of Letters Patent. Patented Aug. 15, 1911.

Application filed January 9, 1911. Serial No. 601,706.

To all whom it may concern:

Be it known that I, ANGUS ALEXANDER MACLENNAN, a citizen of the United States, residing at Buena Vista, in the county of Chaffee and State of Colorado, have invented certain new and useful Improvements in Stovepipe-Cleaners, of which the following is a specification, reference being had to the accompanying drawings.

10 This invention relates to stove pipe cleaners and has for its object to provide an extremely simple, efficient and durable device of this character whereby stove pipe flues may be easily and quickly cleaned.

15 Another object of the invention is to provide a cleaner disposed for movement through the stove pipe consisting of a rod having a scraper fixed to one end thereof for engagement with the walls of the pipe, 20 and means arranged in the pipe about the rod to prevent the escape of soot into the room.

25 With the above and other objects in view, the invention consists of the novel features of construction, combination and arrangement of the parts hereinafter fully described and claimed, and illustrated in the accompanying drawings, in which—

30 Figure 1 is a vertical section through a stove pipe and chimney, showing the arrangement of my improved cleaner in the pipe; Fig. 2 is an enlarged detail section through the packing sleeve or joint through which the cleaner rod is disposed; and Fig. 35 3 is a detail perspective view of the cleaner removed.

35 Referring in detail to the drawing P designates a stove pipe and W the chimney wall into the flue of which one end of the 40 pipe extends. The other end of the pipe is connected to the stove in the usual manner.

E designates the elbow which connects the vertical and horizontal portions of the stove pipe.

45 My improved cleaning device is movably disposed through the elbow of the stove pipe and comprises a rod 5 to the inner end of which the scraper is secured. This scraper is preferably of semicircular form and comprises a sheet of asbestos or steel wool 6. This sheet is arranged between the rigid metal plates 7. The plates 7 are also of semicircular form but of slightly less diameter than the sheet 6 so that the edge 55 portions of said sheet extend beyond the

edges of said plates for contact with the walls of the stove pipe.

In order to prevent the escape of soot and dust into the room or apartment, in the operation of the cleaner, a packing joint or sleeve is arranged in the elbow section E of the stove pipe. This sleeve comprises the two sections 8 and 9, said section 8 having a reduced exteriorly threaded portion 10 for engagement in the interiorly threaded end 65 11 of the sleeve section 9. The latter sleeve section is also provided at the base of the threads 11 with a chamber 12 which is adapted to be filled with asbestos wool or other suitable packing material. Each of 70 the sections is provided with a longitudinal bore 13 through which the cleaner rod 5 extends and is adapted to be moved.

In assembling the device, the sleeve section 9 is first arranged upon the cleaner rod 75 5 and said rod is then passed through the opening in the wall of the elbow E. The other sleeve section 8 is then disposed on said rod and the threaded extension 10 thereof disposed through the opening in the elbow 80 85 and engaged in the threaded bore 11 of the section 9. The end of the section 8 engages the packing material arranged in the chamber 12 of the sleeve section 9 and packs the same closely therein about the rod 5 whereby the liability of dust and soot escaping through the bores of the sleeve sections around the rod is prevented. Upon the outer end of the rod a finger ring 14 is formed through which the operator's finger 90 is adapted to be inserted.

In the use of the device, the operator moves the rod 5 longitudinally in the stove pipe between the chimney flue and the elbow, and during such movement engages the 95 projecting edge portion of the intermediate flexible sheet 6 of the scraper, with the walls of the pipe. The soot and dirt which has collected in the pipe will thus be scraped outwardly into the vertical portion of the 100 pipe and be deposited in the stove from which it may be easily removed. The scraper is adapted to be arranged at any desired angle upon the end of the rod 5, and may be fixed thereon in any desired manner. 105 The rod 5 may be moved in any direction within the stove pipe so as to engage the edge of the scraper with the entire inner surface of said pipe. In the same manner the chimney flue may also be cleaned.

From the foregoing it is believed that the construction and operation of my improved stove pipe cleaner will be readily understood.

The device is simple in construction and 5 may be easily and quickly arranged in operative position.

The principal feature of my invention resides in the manner of mounting the movable rod in the elbow of the pipe whereby the 10 same may be readily moved without danger of the soot escaping into the room.

While I have shown and described the particular form and construction of the various parts, it will be understood that the 15 device is susceptible of considerable modification without departing from the essential feature or sacrificing any of the advantages of the invention.

Having thus described the invention what 20 is claimed is:—

A device of the character described comprising two sleeve sections each having a

longitudinal bore, one of said sleeve sections having an interior annular packing chamber intermediate of its ends, the bore of said 25 sleeve section at one end being enlarged and provided with screw threads, the other of said sleeve sections having a reduced exteriorly screw threaded extension concentric with the bore of said section, said extension 20 being adapted for insertion through a supporting wall and for engagement in the interiorly threaded end of the other sleeve section to compress the packing in the interior chamber thereof, and a cleaner rod longitudinally movable through the bores of said 35 sleeve sections.

In testimony whereof I hereunto affix my signature in the presence of two witnesses.

ANGUS A. MACLENNAN.
